D11-150. OR D17,198 EX

DESIGN.

—o—
C. M. EGBERT.

VASE.

17,198

Patented Mar. 22, 1887.

UNITED STATES PATENT OFFICE.

C. MATILDA EGBERT, OF KANE, PENNSYLVANIA.

DESIGN FOR A VASE.

SPECIFICATION forming part of Design No. 17,198, dated March 22, 1887.

Application filed February 16, 1887. Serial No. 227,968. Term of patent 14 years.

To all whom it may concern:

Be it known that I, C. MATILDA EGBERT, of Kane, in the county of McKean and State of Pennsylvania, have invented and produced 5 a new and original Design for a Monumental Vase, of which the following is a specification, reference being had to the accompanying drawing, forming a part thereof.

The drawing represents a view in perspective of a vase embodying my design.

The leading features of my design comprise a vase-body having the appearance of a cornucopia, a lamb couchant, upon which the cornucopia appears to rest, and flying cherubs on 15 opposite sides of the mouth of the cornucopia, appearing as if bearing the vase upward.

A designates the body of the vase, which resembles in shape a cornucopia having its smaller or tip end downward, and an ornamental border or rim, b, at its upper and larger or mouth end.

B is a figure representing a lamb couchant upon an oval or other shaped base, C, and appearing as if supporting upon its back the cornucopia or vase-body by its tip end, and D 25 are figures representing cherubs upon opposite sides of the upper or mouth end of the cornucopia-shaped body A, each cherub ap-

pearing as volant and with its hands outstretched and applied to the rim or mouth end 30 of the vase-body, as if bearing the vase upward.

I claim—

1. In a design for a vase, the body of the vase shaped to represent a cornucopia, and a 35 figure representing a lamb couchant, upon the back of which the tip end of the cornucopia appears to rest, as herein shown and described.

2. In a design for a vase, the body of the vase shaped to represent a cornucopia, and 40 figures resembling cherubs with outstretched arms applied to the mouth end of the cornucopia as if lifting it, as herein shown and described.

3. The design for a vase herein shown and 45 described, the same consisting of figures representing a lamb couchant, a cornucopia resting at its tip end upon the lamb, and cherubs volant, with their hands applied to the rim at the mouth end of the cornucopia, as if bearing 50 the vase upward.

C. MATILDA EGBERT.
